MOUNT FOR TRACTOR CANOPY POST
Donald L. Wood, Medford, Oreg., assignor to Concrete-
Steel Corporation, a corporation of Oregon
Filed July 15, 1965, Ser. No. 472,189
13 Claims. (Cl. 287—20)

ABSTRACT OF THE DISCLOSURE

A post mount including a vertically projecting pedestal securable to a portion of a tractor, a closed end resilient cushioning boot is received over the pedestal and is in turn surrounded by an elongated collar. A post receiving adapted is secured to the upper end of the collar and engages the upper or closed end of the boot. The adapter includes a plurality of concentric upwardly directed offset shoulders for the reception of the hollow lower end of a variety of different sized tractor canopy posts which are to be received on the appropriate shoulder and welded thereto.

The instant invention generally relates to tractor canopies, and is more specifically involved with the provision of cushioning mounts for the posts thereof.

It is one of the primary intentions of the instant invention to provide for the mounting of a tractor canopy in a manner which is contemplated to effectively dampen the noise and vibrations normally associated therewith during the operation of the tractor, the vibrations significantly contributing to the structural failure of the various canopy members or joints therebetween.

In conjunction with the above object, it is also a significant object of the instant invention to provide for a bolt locking of each post in a manner whereby the bolt itself, while preventing a disengagement of the post end from the tractor, performs no substantial weight bearing functions.

Further, it is a significant object of the instant invention to provide for a post mount wherein a major safety factor is provided in that even were the related locking bolt to break, the canopy post would still not, under normal circumstances, disengage from the tractor.

Furthermore, it is an object of the instant invention to provide a mount structure which is intended to have an extremely long life due to the absence of direct metal-to-metal contact between relatively movable parts. By the same token, normal maintenance is to be reduced to merely an occasional replacement of the rubber cushioning boots which can be quickly slid into place without the necessity of cutting, welding, etc.

Likewise, it is an object of the instant invention to provide a tractor canopy mount wherein a slight movement of the canopy is allowed and provided for so as to effectively absorb shock and correspondingly reduce the structural stresses resulting from the operation of the tractor.

In addition, an important object of the instant invention resides in the provision of a mount which is specifically constructed so as to accept any of a plurality of different size canopy posts so as to provide in effect a universal mount.

Basically, the post mount of the invention comprises a vertically projecting pedestal secured to a portion of the tractor, a closed end resilient cushioning rubber boot received over the pedestal, an elongated collar surrounding the boot, and a post receiving adapter welded to the upper end of the collar and engaged with the upper or closed end of the boot, the adapter and collar forming in effect a downwardly opening socket. The adapter in-

2

cludes a plurality of concentric upwardly directed offset shoulders for the reception of the hollow lower end of a variety of different sized tractor canopy posts which are to be received on the appropriate shoulder and welded to the adapter. In addition, the adapter includes a downwardly directed shoulder which seats the upper end of the collar which is in turn also welded thereto, the lower face of the adapter including a central recess so as to insure a proper seating on the top of the rubber boot covered pedestal. The collar includes a full height slot therein so as to define free ends which can be selectively drawn together so as to tighten the collar about the boot covered pedestal, the boot itself including a slide resilient rib projecting outwardly therefrom and being snugly received within the slot, this rib providing a smooth exterior with the collar and acting so as to both prevent relative rotation between the boot and collar and cushion the adjacent vertical edges of the collar as it clamps on the boot. The actual clamping of the collar about the pedestal cover is effected by an elongated bolt received through diametrically opposed openings in both the boot and collar and through an elongated opening or passage through the pedestal, the pedestal passage having an enlarged cross-sectional area which will accommodate movement of the collar, and consequently, the canopy post, relative to the pedestal, to a slight degree, this movement being cushioned by the boot and ultimately limited by the bolt. Further, the lower end of the collar is spaced upwardly from the base of the pedestal whereby no direct canopy weight is introduced into the bolt itself with the socket nature of the collar tending to maintain a safe engagement with the pedestal even should the bolt break for any reason.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the mount of the instant invention and the adjacent portions of the canopy post and tractor;

FIGURE 2 is an enlarged cross-sectional view taken substantially on the plane passing along line 2—2 in FIGURE 1;

FIGURE 3 is an enlarged transverse cross-section taken substantially on the plane passing along line 3—3 of FIGURE 1;

FIGURE 4 is an exploded perspective view of the various elements of the mount;

FIGURE 5 is a cross-sectional view similar to FIGURE 2 and illustrating the accommodation of a smaller canopy post on the mount; and

FIGURE 6 is a partial exploded perspective view illustrating a modification of the instant invention.

Referring now more specifically to the drawings reference numeral 10 is used to generally designate the canopy post mount comprising the instant invention. The mount 10 is to be fixed to and project vertically upward from the tractor 12 itself, a small portion thereof being illustrated in FIGURE 1, with the engagement of the mount 10 to the tractor 12 normally being effected through a suitable bracket 14, the shape thereof depending upon the particular portion of the tractor engaged thereby. For example, the angular bracket 14 illustrated in the drawings is particularly adapted for use in mounting the forward canopy posts on the tractor fenders. The canopy post 16 will of course be engaged with the upper end of the mount 10 in a manner which shall presently be described.

The mount 10 itself includes a solid cylindrical pedestal having a flat upper end 20 and a flared or enlarged cylindrical base end 22. This enlarged base end 22, as will be

appreciated from the drawings, in rigidly fixed, as by welding 24, to the mounting bracket 14 which in turn is rigidly affixed, as by welding 26, to the tractor 12 itself. Incidentally, if appropriate, the enlarged pedestal can of course be affixed directly to the tractor without using the bracket 14. Finally, the pedestal 18 includes a vertically elongated passage 28 diametrically therethrough at approximately mid-height.

Slidably mounted over the pedestal 18 is a closed end resilient cushioning boot 30, this boot 30 having the closed end 32 thereof seated on the upper flat end 20 of the pedestal and the lower open end thereof positioned in spaced relation slightly above the enlarged pedestal base 22.

Further, as will be appreciated from the drawings, the rubber cushioning boot 30 includes an integral outwardly projecting resilient rib 34 extending longitudinally therewith for the full length thereof, as well as a pair of diametrically opposed openings 36 which are smaller than the pedestal opening or passage 28 and alignable with the opposite ends thereof.

Next, an elongated split cylindrical collar 38 is snugly received about the cylindrical boot 30 with the slot or slit 40 therein receiving the boot rib 34, this rib 34 being closely received within the slot 40 and projecting to a point substantially coplanar with the outer surface of the collar 38 so as to form a substantial smooth continuation thereof. The collar 38 also includes a pair of diametrically opposed bolt holes 42 which align with the boot holes 36 upon a positioning of the boot rib 34 within the collar slot 40. In this manner, it will be appreciated that relative movement between the boot and collar is prevented, thereby maintaining the alignment of the holes 36 and 42.

Next, a post receiving adapter 44 is fixed to the open end of the collar 38 and forms in effect an inverted socket therewith for reception over the boot 30, the lower surface 46 of the adapter 44 bearing against the closed top end 32 of the boot 30 while the open lower end of the collar 38 is spaced upwardly of the pedestal base 22 and in approximately the plane of the open lower end of the boot 30. The lower portion of the adapter 44 is of a size so as to be received within the upper end of the collar 38 with an integral annular projection 48 being formed above the lower end of the adapter 44 and extending outwardly to approximately the outer circumference of the collar 38, thereby defining both a downwardly directed shoulder 50 and an upwardly directed shoulder 52. The downwardly directed shoulder 50, as will be best appreciate from FIGURES 2 and 5, is seated on and welded to the upper end of the collar 38. The upwardly directed shoulder 52 is the largest of a series of concentric progressively decreasing shoulders 52, 54 and 56, all extending annularly about the upper portion of the adapter. The significance of the progressively decreasing shoulders 52, 54 and 56 is to adapt the mount 10 so as to accommodate conventionally provided different diameter tractor canopy posts 16, this best being appreciated from a comparison of FIGURES 2 and 5, FIGURE 5 illustrating the use of the adapter 44 in accommodating a substantially smaller canopy post 16'.

Finally, in order to lock the various elements together, an elongated bolt 58 is extended through the aligned holes 28, 36 and 42, the bolt 58 having an enlarged head 60 on one end thereof and a threaded nut 62 on the other end thereof whereby, upon a tightening of the nut 62, an inward flexing of the collar 38 is provided. This inward flexing of the collar 38 is possible because of the presence of the slot 40 therein, and results in a cushioned clamping of the collar 38 to the pedestal 18 with the resilient boot 30 interposed therebetween. With reference to FIGURE 2, it will be noted that the enlarged opening 28 within the pedestal 18 allows for a limited vertical movement of the collar 38 relative to the pedestal 18, thereby enabling the accommodation of slight movements of the canopy without the introduction of undue stress at the joint. This

movement is of course cushioned by the boot 30 and ultimately limited by the bolt 58, no metal-to-metal contact occurring between the collar 38 and the pedestal 18 during this movement. Further, inasmuch as the bottom surface 46 of the adapter 44 sits directly on the upper end 20 of the pedestal 18 through the upper end 32 of the boot 30, the bolt 58 itself does not have to accommodate the weight of the canopy, this weight instead of being transferred directly to the tractor through the pedestal 18. Further, it will be noted that the bottom surface 46 of the adapter 44 is centrally relieved or recessed as at 64 so as to provide for a stable seating on the boot covered pedestal top 20. Of particular significance is the factor of safety introduced into the particular mount so constructed, in that even if for some reason the bolt 58 should break, a positive mounting of the canopy post to the tractor would still be present and would be maintained, under normal conditions, until suitable repairs could be made.

With particular reference to FIGURE 6, it will be appreciated that a modified form of adapter 44' has been illustrated therein, this adapter 44' having a generally square configuration, at least insofar as the shoulder forming portions thereof are concerned, for the accommodation of various sizes square canopy posts 16". The adapter 44' will of course be utilized in the same combination of elements as shown in FIGURE 2 in conjunction with the circular adapter 44.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A mount for a canopy post comprising a projecting pedestal, said pedestal having a fixed end and a free end, a resilient cushioning boot received over said free end and enclosing a major portion of said pedestal, an elongated collar encircling said boot, a post receiving means fixed to one end of said collar and overlying the free end of said pedestal, said post receiving means having a plurality of differently sized offset portions thereon to receive various sized hollow post ends, and fastener receiving aligned apertures through diametrically opposed portions of said boot and collar and the pedestal received therein.

2. A mount for a canopy post comprising a projecting pedestal, said pedestal having a fixed end and a free end, a resilient cushioning boot received over said free end and enclosing a major portion of said pedestal, an elongated collar encircling said boot, a post receiving means fixed to one end of said collar and overlying the free end of said pedestal, and fastener receiving aligned apertures through diametrically opposed portions of said boot and collar and the pedestal received therein, said post receiving means including a plurality of concentric offset shoulders thereabout, said shoulders being forwardly directed relative to the free end of the pedestal for the selective reception of hollow post ends of varying sizes.

3. The structure of claim 2 wherein said boot includes a closed end overlying the free end of the pedestal beneath said post receiving means.

4. The structure of claim 3 wherein said collar includes a full length slot through the height thereof, said slot allowing for a slight flexing of said collar.

5. The structure of claim 4 including an elongated resilient rib projecting outwardly from said boot, said rib being received within and substantially filling the collar slot.

6. The structure of claim 5 wherein the boot and collar apertures are of a size so as to closely receive a predetermined size fastener therethrough, the pedestal aperture being substantially larger in cross-sectional area so

as to allow for a limited movement of the fastener therein.

7. The structure of claim 6 wherein the inner end of the post receiving means includes a recessed central portion defining a surrounding edge portion seatable on the closed end of the boot.

8. The structure of claim 7 wherein said post receiving means includes a collar seating shoulder receiving said one end of said collar, said collar seating shoulder being oppositely directed relative to said first mentioned shoulders.

9. The structure of claim 3 wherein the boot and collar apertures are of a size so as to closely receive a predetermined size fastener therethrough, the pedestal aperture being substantially larger in cross-sectional area so as to allow for a limited movement of the fastener therein.

10. A mount for a canopy post comprising a projecting pedestal, said pedestal having a fixed end and a free end, a resilient cushioning boot received over said free end and enclosing a major portion of said pedestal, an elongated collar encircling said boot, a post receiving means fixed to one end of said collar and overlying the free end of said pedestal, and fastener receiving aligned apertures through diametrically opposed portions of said boot and collar and the pedestal received therein, said collar including a full length slot through the height thereof, said slot allowing for a slight flexing of said collar.

11. The structure of claim 10 including an elongated resilient rib projecting outwardly from said boot, said rib

being received within and substantially filling the collar slot.

12. A mount for a canopy post comprising a projecting pedestal, said pedestal having a fixed end and a free end, 5 a resilient cushioning boot received over said free end and enclosing a major portion of said pedestal, an elongated collar encircling said boot, a post receiving means fixed to one end of said collar and overlying the free end of said pedestal, said post receiving means having a plurality of different sized offset portions thereon to receive various sized hollow post ends, and fastener means engaging said collar to said pedestal with said resilient cushioning boot therebetween.

13. The structure of claim 12 wherein said differently 15 sized offset portions are concentrically arranged and of a radially reduced size sequentially outward relative to the free end of the pedestal.
